COUNTER MOLDING MACHINE

Leslie Hugh Bennion, Leicester, England, assignor
to United Shoe Machinery Corporation, Paterson, N. J., a corporation of New Jersey

Application September 30, 1935, Serial No. 42,855
In Great Britain October 19, 1934

11 Claims.

(Cl. 12—66)

This invention relates to machines for shaping shoe part blanks and is herein illustrated as embodied in a counter molding machine of the type disclosed in the United States Letters Patent No. 5 1,138,123, granted May 4, 1915, upon an application filed in the name of R. A. Lancey.

One type of heel stiffener or counter which has come into general use in the manufacture of shoes comprises a counter in which one or both 10 of the wing portions are lengthened to extend well into the shank or waist portion of the shoe in which it is assembled to provide support at one or both sides for the arch of the foot. It is an object of the present invention to provide an improved counter molding machine having mechanism particularly adapted for quickly and conveniently shaping the wing portions of counters of this type.

To this end and as illustrated, the invention 20 consists in the provision of a machine having molds for shaping the heel-end portion of a counter blank, wiping means to form a flange upon the blank and to shape the wing portions thereof, together with means adapted, during the movement of the wiping means, to control the pressure exerted upon the blank. Preferably and as shown, the molds have faces portions of which are curved for cooperation with a wiper member 25 movable along the faces to shape the wing portions of the counter, the wiper member being pivotally mounted so that it can conform to the curvature of the faces. Preferably too, the wiper member is forced against the blank by means which is caused to yield by predetermined 30 amounts dependent upon the position of the wiper member, thereby to control the pressure of the member upon the blank.

The mechanism set forth is particularly effective for molding counters of the type referred to 40 in view of the fact that although the curvature of the extremities of the wing portions of the counters which are to be molded may vary sharply, the pivoted wiper member adjusts itself to the variations in the curvature without applying such 45 excessive pressures to the wing portions of the counter blank as would tend to damage the material. This arrangement is also advantageous in that it facilitates the presentation of the counter blank to the machine rapidly and with- 50 out likelihood of injury to the operator.

The various features of the invention are described in the following detailed specification, are illustrated in the accompanying drawings and will be pointed out in the claims.

55 In the drawings,

Fig. 1 is a front elevation of a portion of a counter molding machine embodying one form of the invention;

Fig. 2 is a side elevation partly in section illustrating details of the wiping mechanism;

Fig. 3 is a view similar to Fig. 2 illustrating parts of the wiping mechanism in the position they occupy at the end of their wiping movement;

Fig. 4 is a front elevation of part of a counter 10 molding machine embodying a modified form of the invention;

Fig. 5 is a side elevation partly in section of the wiping mechanism shown in Fig. 4 with the parts in the positions they occupy before the machine 15 commences to operate; and

Fig. 6 is a view similar to Fig. 5 but showing the position of the parts at the end of a counter molding movement.

One embodiment of the invention is illustrated 20 in Figs. 1, 2 and 3 of the drawings which show a counter molding machine comprising a frame 10 which supports an inner mold 12 and a pair of outer molds 14 arranged for operation upon a counter such as a counter 16 (Fig. 3) to form the 25 curvature of the side walls thereof, a reciprocating wiper plate 18 for forming the flange portion 20 of the counter at the heel end thereof, and an auxiliary wiper plate 22 operable upon the counter blank to form flanged portions along the 30 wings of the counter. The mechanism for operating the inner and outer molds and the wiper plate 18 is not shown in detail but may be of any construction common to the prior art such as that of the above mentioned United States Letters 35 Patent.

The auxiliary wiper plate 22 is pivotally mounted 40 for movement outwardly of the inner mold 12, thus to provide for variation in curvature of the mold in producing the flanges on the wing portions of the counter. To this end the wiper plate 18 has pivoted to it a pair of depending arms 24 pivoted at their upper ends on the ends of a pin 26 by which the wiper plate 18 is connected to its actuating rod 28. The arms 24 are urged toward 45 the wiper plate 18 by springs 30 surrounding studs 32 secured in the wiper plate 18 and passing through openings in lateral extensions 33 of the arms. The springs 30 are confined between the arms 24 and adjustable nuts 34 on the studs. 50 Movements of the arms 24 toward the wiper plate 18 are limited by an adjustable screw 36 threaded through a bar 38 joining the two arms together. At their lower ends the arms 24 carry the wiper plate 22 pinned to the arms by a pivot pin 40 55

which extends through a block 42 forming part of the plate. A leaf spring 44 secured to the pin 36 bears, at its lower end, against the lower margin of the block 42 and tends to swing the lower margin of the plate about the pin 46 toward the inner and outer molds 12 and 14. Movement of the wiper plate 22 about the pin 46 in this direction is limited by the engagement of the plate with faces 46 (Fig. 3) formed on the lower ends 10 of the arms 24. The upper part of the inner mold 12 is shaped for molding counters of usual form and below this part and merging into the front face of the mold is a downwardly and forwardly extending curved face 48 suitably shaped for the 15 molding of the forwardly projecting wing portion or portions of the counter. The two parts of the outer molds 14 are extended downwardly and their front faces are curved forwardly at their lower ends as shown at 50 (Fig. 2). 20

The rear face 52 of the plate 22 is curved to conform to the curvature of the inner and outer molds and as the wiper plate 18 and the wiper plate 22 move downwardly over the faces of the molds the wiper plate can move forwardly bodily 25 about the axis of the pin 26 and can tip about the pin 46 as it moves along the curved faces of the molds. Each of the outer molds has secured to it a track 54 against which the wiper plate 22 bears as it moves along the curved portions of the 30 molds. The front faces of the tracks 54 are curved to conform to the curvature of the curved portion of the inner mold and extend slightly forwardly of the front face thereof merging with the front faces of the flat parts of the outer molds 35 14. While the plate 22 bends over and presses the margin of the counter along the curved portion of the inner mold 12 part of the pressure of the plate is taken by the tracks 54 which prevent the lower edge of the plate from digging 40 into the counter and possibly tearing it as it might do if the lower edge of the plate were forced forwardly by its engagement with the curved surface of the counter. The tracks 54 are preferably slidably mounted in the molds 14 45 so that they can be adjusted to position more or less of their length beyond the forward faces of the molds, thus to control the pressure of the plate 22 against the counter being operated upon. The lower edge of the plate 22 has a curved recess 50 56 which engages the margin of the counter at the heel end and is operative to turn in and mold the flange of the counter so that the pleats formed in the margin of the flange are more or less evenly distributed about the heel end thereof. 55

In the operation of the machine after a counter blank has been placed between the inner mold and the outer mold and gripped by them the wiper plate 18 and the plate 22 are moved downwardly and the lower edge of the plate 22 is 60 pressed rearwardly by the leaf spring 44, engaging the projecting margin of the counter blank close to the molds, and operates to turn the margin inwardly over the front face of the inner mold 12 with a yielding pressure which is dependent upon the strength of the springs 30. The wiper plate 18 presses the inturned flange against the inner mold 12 with a considerably greater and unyielding pressure. When the plate 22 reaches the curved parts 48 of the molds the plate rides 65 along the tracks 54 and is moved forwardly by them about the pin 26 and about the pin 46, thus permitting the wiper plate to conform itself to the shape of the curve. In its movement along the tracks 54 the plate 22 bends the margin of 70 75 the counter inwardly over the inner mold 12 and

presses it against the face of the mold. This arrangement thus enables a sufficiently heavy pressure to be applied to the counter blank along the curved parts of the mold effectively to mold the margins of the counter along those parts without likelihood of damaging the material by pressure of the wiper plate 22 which increases as the plate moves along the curved portions of the molds due to the action of the springs 30. 5

Figs. 4, 5 and 6 illustrate an alternative form 10 of invention. The machine shown therein comprises a frame 58, an inner mold 60, outer molds 62, and a slidable flange former 64 operated by an actuating rod 66, these parts being similar to those embodied in the mechanism above described. The flange former 64 has pivoted to it a pair of depending arms 68 which are pivotally mounted on a pin 70 carried by the flange former 64 with arms 68 at their lower ends carrying a pin 72 (Figs. 5 and 6) upon which is pivotally mounted an auxiliary wiper plate 74 having a curved work-engaging face 76. The pin 72 is in front of the face 76 of the plate and is positioned at about the middle of the plate considered heightwise thereof. The curvature of the rear face 76 of the plate 74 conforms to the curvature of the forwardly curved faces 78 of the inner and outer molds 60 and 62. 20

In order to maintain the auxiliary wiper plates 30 74 in engagement with the faces of the molds the arms 68 are provided with a bar 80 which has secured in it a pin 82 passing through a slot in a lug 84 extending from the plate 74, there being a spring 86 confined between the bar 80 and the lug 84 for forcing the plate about its pivot 72 in a direction to maintain the face 76 in engagement with the work as the wiper is moved downwardly along the faces of the molds. 35

Pivoted on the pin 72 are the rear ends of links 88, the forward ends of which are pivotally connected by a pin 90 to links 92 mounted upon a pin 94 carried by arms 96 extending forwardly from the flange former 64. Pivoted on the pin 90 are upwardly extending rods 98 which pass through lugs 100 projecting outwardly 45 from the flange former 64. The rods 98 at their upper ends carry springs 102 which engage the lugs 100 and the adjustable nuts 104 on the upper ends of the rods. The springs 102 act to press, through the links 88 and 92, the wiper plate 74 50 toward the faces of the molds and against the flange portions of a contour blank when positioned upon the inner mold. This arrangement of links 88, 92 and rods 98 operates to control the pressure of the wiper plate 74 against a counter 55 blank as the plate moves along the curved faces 78 of the molds. As this occurs the springs 102 are compressed since as the plate 74 moves forwardly the axes of the rods 98 approach the axis of the pin 94 with the result that the increasing 60 thrust of the springs 102 due to their further compression is taken by the pin 94 and the plate is pressed against the counter with substantially the same pressure as when the plate 74 is moving along the straight portions of the molds. 65

In the operation of the machine after a counter blank has been placed between the inner and outer molds and gripped by them the flange former 64 and wiper plate 74 are moved downwardly and the lower portion of the plate, then 70 held in the position shown in Fig. 5 by the spring 106, engages the projecting margin of the blank and turns the margin inwardly over the front face of the inner mold with a yielding pressure which depends upon the force exerted by the 75

5 springs 102 which tends to move the rod 98 upwardly and which is controllable by adjustment of the nuts 104 on the rod. When the plate 74 reaches the curved faces 78 of the molds the plate is moved forwardly about the pin 70 and 10 tilts about the pin 72. As the plate 74 moves about the pin 70 the springs 102 yield permitting the pin 90 to move downwardly and forwardly about the pin 94, as shown in Fig. 6, so that the 15 increased pressure of the springs 102 caused by outward movement of the plate is applied to the pivot 94 instead of to the wiper plate thus avoiding any likelihood of marring the wing portions of the blank.

15 Having described my invention, what I claim as new and desire to secure by Letters Patent of the United States is:

1. A counter molding machine comprising molds for shaping the side and rear portions of 20 a counter blank and having faces portions of which are curved, a flange former movable across the faces of the molds to form a flange on the blank, a wiper movable along the faces of the molds to shape wing portions of the blank, means 25 for forcing the wiper toward the faces of the molds, and means for limiting to an approximately constant amount the pressure exerted by the wiper upon the curved portions thereof.

2. A counter molding machine comprising 30 molds for shaping the side and rear portions of a counter blank and having faces portions of which are flat and other portions of which are curved, a flange former movable across flat portions of said faces to form a flange on the blank, 35 a wiper pivotally mounted upon the flange former and movable in advance thereof along the faces of the molds to shape wing portions of the blank, yieldable means for forcing the wiper toward the faces of the molds, and means for limiting the 40 pressure exerted by the wiper upon curved portions of the faces to an amount not substantially greater than the pressure exerted by the wiper upon the flat portions of the surfaces.

3. A counter molding machine comprising 45 molds for shaping the side and rear portions of a counter blank, a flange former movable along faces of the molds to form a flange on the blank, a wiper pivotally mounted upon the flange former and in advance thereof for shaping wing portions 50 of the blank, a pair of rods loosely mounted upon the flange former, links connecting the rods and the flange former, other links connecting the rods and the wiper, and springs associated with the rods for moving the rods and 55 links in a direction to cause the wiper to exert pressure upon the faces of the molds.

4. A counter molding machine comprising 60 operating molds for shaping the side and rear portions of a counter blank, a flange former movable along the faces of the molds, a wiper pivotally mounted upon the flange former, and means for controlling the pressure exerted by the wiper upon the faces of the molds comprising a pair of rods loosely mounted upon the flange former, 65 links connecting the lower ends of the rods with the flange former and with the wiper, and means for forcing the rods in a direction to force the wiper toward the faces of the molds.

5. A counter molding machine comprising co-

operating molds for shaping the body portion of a counter blank, one of the molds having an outwardly curved face, a wiper movable along said face to shape wing portions of the blank, yieldable means for forcing the wiper toward the face, 5 and means for maintaining approximately constant the pressure applied by the yieldable means to the wiper as it moves along the face.

6. In a counter molding machine comprising inner and outer molds for shaping the side and rear portions of a counter blank, the inner mold having a face portions of which are curved, a wiper mounted for movement along said face for shaping wing portions of the blank, means for forcing the wiper toward the said face, and 15 means for maintaining approximately constant the pressure of the wiper against said face during the movement of the wiper along the curved portions thereof.

7. In a counter molding machine comprising 20 molds for shaping the body portion of a counter blank and a flange former, a wiper pivotally mounted upon the flange former and movable therewith along the faces of the molds to shape wing portions of the blank, links pivotally connecting the wiper and the flange former, a member for actuating the links to force the wiper toward the faces of the molds and movable angularly as the wiper moves along curved faces of the 25 molds to maintain the pressure exerted by the 30 wiper upon the molds approximately constant.

8. A counter molding machine comprising co- 35 operating molds for shaping the body portion of a counter blank, one of the molds having a curved face, a wiper movable along said face for shaping wing portions of the blank, and means for forcing the wiper toward said face comprising a toggle which is yieldable as the wiper moves along 40 said face to maintain the pressure of the wiper upon said face approximately constant. 40

9. A counter molding machine comprising co- 45 operating molds for shaping the body portions of a counter blank, a flange former, a wiper member pivotally mounted upon the flange former, yieldable means for forcing the wiper member 45 toward the faces of the molds, and means carried by one of the molds for limiting inward movement of the wipers.

10. A counter molding machine comprising co- 50 operating molds for shaping the body portion of a counter blank and having curved faces, a flange former movable across the faces of the molds, a wiper member pivotally mounted upon the flange former, yieldable means for forcing the wiper member toward the faces of the molds, and 55 tracks carried by the molds for limiting inward movement of the wiper along the curved portions of the faces.

11. A counter molding machine comprising in- 60 ner and outer molds for shaping the body portion of a counter blank, the inner mold having a curved face, a wiper movable along the curved face for shaping wing portions of the blank, and tracks carried by the outer molds and projecting beyond the face of the inner mold for controlling 65 the pressure of the wiper upon the face of the inner mold.

LESLIE HUGH BENNION.
